Parker & Burton

ATTORNEY.

UNITED STATES PATENT OFFICE.

WILLIAM WATT McEWAN, OF DETROIT, MICHIGAN, ASSIGNOR TO THE J. B. FORD COMPANY, OF WYANDOTTE, MICHIGAN.

WASHING MACHINE.

Application filed June 13, 1925. Serial No. 36,849.

My invention relates to improvements in washing machines and is here illustrated in connection with a dish washing machine though obviously it might be employed in 5 machines for washing articles other than dishes.

At the present time in washing machine practice washing powder is deposited in the vat of the washing machine from time to time 10 by the operator as he believes it is needed. The supply is irregular and the washing solution in the vat varies from one period to another and is not kept at a constant or uniform strength throughout the washing operation. The powder sinks to the bottom of the 15 vat or comes directly in contact with the dishes. At one period the supply is in excess of that necessary for the washing operation while at another time it is insufficient. The 20 powder is not properly dissolved in the vat and it is not practicable to provide means in the vat to perform such function.

I provide a washing machine having a vat 25 in which the dishes are washed with an independent solution tank within which the washing powder is first completely dissolved by improved mechanism and from which tank it is withdrawn into the washing machine vat as it is needed and the solution within the vat 30 is maintained at a substantially constant and uniform strength throughout the entire washing operation.

In the beginning of a washing operation it 35 is preferable to deposit within the solution tank a sufficient quantity of washing powder to complete the operation intended and due to the employment of my improved mechanism this washing powder is completely dissolved and the concentrated solution is permitted 40 to flow as required from the solution tank into the vat of the washing machine where the washing operation occurs. The wash water in the vat is thereby maintained at a substantially uniform strength and at 45 that strength which has been found most suitable for the washing purpose without using washing powder in excess of the amount required.

The above objects and others, together with 50 details of construction of the embodiment of my invention illustrated in the drawing will more fully appear from the following de-

scription, claims and accompanying drawing, in which:

Figure 1 is a side elevation of a machine 55 fitted with my improvement.

Fig. 2 is a vertical sectional view taken on line 2—2, Fig. 1.

Fig. 3 is a horizontal sectional view taken 60 on line 3—3, Fig. 2.

I have illustrated my improvement in association with a dish washing machine and in Fig. 1 the dish washing machine proper is indicated as 10. This machine is provided with a washing vat 12 within which the washing solution is carried and the washing occurs. The detailed structure of the dish washing machine proper forms no part of my invention and is, therefore, not described.

I provide an independent solution tank 14 70 of a size suitable to feed the vat of the particular washing machine in connection with which it is to be employed. This solution tank communicates with the vat of the dish washing machine shown in the drawing by means of a conduit 16, the flow of liquid 75 through which is controlled by a valve 18. Water is supplied to the solution tank 14 through a water pipe 20 which leads from a suitable source of water supply, preferably 80 hot water, and which in turn is fitted with a control valve 22. The solution tank has a cover 24 which may be raised to deposit washing powder into the tank. At one side of the solution tank is a water glass 26 to indicate 85 the amount of water carried within the tank.

As the solution tank carries a concentrated washing solution which is admitted from time to time into the vat of the washing machine during the washing operation, it is 90 necessary that the solution within the tank 14 be maintained at a substantially uniform strength throughout the entire washing operation, and furthermore, it is desirable that all the washing powder placed within the 95 tank be completely dissolved in order that full value may be obtained therefrom without the use of an excess amount. I provide a pipe 28 leading from a suitable source of steam supply and controlled by valve 30, 100 which pipe terminates within the solution tank in an extension 32 positioned in the bottom of the tank and perforated to project a plurality of steam jets through the contents

of the tank and agitate the solution, heat the water, and completely dissolve the soap powder and maintain the entire solution at a substantially uniform strength.

- 5 At the beginning of the washing operation a sufficient amount of washing powder is placed within the solution tank to take care of the intended operation of washing and the tank filled with water through the pipe 20.
- 10 Steam is now admitted through the steam pipe 28 through control exercised thereover by the valve 30. This steam pipe extends downwardly through the solution to a T-shaped extension disposed at the bottom of
- 15 the tank provided with a multiplicity of perforations which project jets of steam throughout the contents of the tank, agitating the solution, dissolving the powder and maintaining the strength of the concentrated solution
- 20 substantially uniform. This concentrated solution is now drawn off through the discharge outlet 16 and admitted to the washing vat 12. It may be drawn off from time to time as needed or the valve 18 may be set to allow the
- 25 concentrated solution to trickle into the washing vat without any further attention on the part of the operator. The concentrated solution is freely miscible with the water in the vat and serves to keep the same at the required
- 30 constant strength.

What I claim is:

1. A solution tank for a washing machine having a controlled water inlet leading from

a suitable source of supply and a controlled steam inlet leading from a suitable source of steam supply into the upper portion of the tank and downwardly therethrough and terminating in proximity to the bottom of the tank in a perforated T-shaped extension disposed to project steam jets upwardly through the contents of the tank.

2. A pre-soap solution tank for dish washing machines adapted to be supported in close proximity to the dish washing vat and having a controllable pipe connection extending from the bottom of the tank to feed soap solution to the vat, said tank having a controlled water inlet leading from a suitable source of supply and a separate controlled steam inlet leading from a suitable source of steam supply into the upper end of the tank and extending downwardly therethrough in close proximity to one of the side walls thereof and having a perforated T-shaped extension disposed substantially parallel with said side wall of the tank and disposed to project steam jets upwardly through the contents of the tank, said steam jets agitating the supply of soap and water therein and heating the same to thereby completely dissolve the soap powder and maintain the entire solution at a substantially uniform strength.

In testimony whereof, I sign this specification.

WILLIAM WATT McEWAN.
